UNITED STATES PATENT OFFICE

2,460,624

COFFERDAM

Curzon Dobell, New York, N.Y., assignor to Pre-load Enterprises, Inc., a corporation of Delaware

Application November 13, 1945, Serial No. 627,990

4 Claims. (Cl. 61—34)

1.

This invention relates to cofferdams and consists in a new and improved process of constructing cofferdam barriers for use where it is desired to expose a normally submerged surface.

An important field of use of my novel process is in repairing sections of river-retaining walls or dams, or for building concrete linings or facings for rivers or reservoirs where the submerged surfaces are irregular in contour or where for any reason it is not possible or convenient to drive interlocking piles to provide the desired enclosure. Going more into detail, the process of my invention is useful for repairing or reconditioning concrete-lined areas of a river bank where very expensive cutting would otherwise be necessary in order to drive piles through the concrete and into the river bed.

The invention contemplates a novel method of forming a cofferdam or barrier which consists first in the placing of adjacent and cooperating blanket supporting surfaces within the body of water about the area to be exposed and extending upwardly from the bottom thereof, and second the placing of water excluding blankets in overlapping relation on said surfaces and extending outwardly therefrom along and on the bottom of said body. The surface supported portion of the blankets provides a wall preventing the free passage of water to said area and the portion of the blankets resting on the bottom prevents percolation of water through the bottom and under the barrier by extending the blanketed area a substantial distance outwardly of the barrier. I propose to utilize flexible water-excluding blankets to cover both the submerged surface or bottom adjacent to the barrier and the walls of the barrier itself.

Another characteristic feature of my novel process consists in forming the barrier of articulated frames which may be rendered buoyant and floated into place and then sunk in exactly the proper location to form the component parts of the barrier. The individual frames may be rendered buoyant by the provision of air tanks and may be balanced and caused to float in the desired or convenient position by adjusting the contents of the buoyant floats or the position of the blanket which I propose to attach in rolled formation to each section. These fabric rolls are of substantial weight and may be partially

2.

unrolled upon their respective frames in adjusting the center of gravity of each frame.

The barrier sections may be separately constructed and comprise a timber frame with a sheathed outer facing upon which the fabric blanket is to be supported. The individual frames may be of such dimension as to withstand the racking and twisting of rough water, for example, 20 feet in length. These unit sections 10 may be assembled in articulated relation on one or more cables and towed in train from one location to another. In transit the individual frames are free to toss and pitch and then, when they have been properly located in the desired position, they may be bound together by tightening of the cables and sunk to form the longitudinal element of the cofferdam. For example, a string of 20 and 22 sections may be handled together in this way.

20 In the application of my process to sloping surfaces such as a river bank, the bottom of each section will, of course, be designed to rest in an inclined position and the projection of its center of gravity will fall within the middle third of 25 the base and thus render it stable against uplift or overturning after the cofferdam has been pumped out.

The process of my invention can be utilized for uncovering (1) a submerged surface which is 30 inclined, (2) an inclined surface merging into a horizontal surface, (3) a horizontal surface, and (4) a vertical surface as, for example, the vertical wall of a dam. In all four of these cases, the frames are made of suitable shape for their 35 intended use, are made substantially waterproof by a fabric blanket or curtain, and the blanket is extended out from the walls of the frames over any desired area of the porous material or the irregular surface upon or against 40 which the frames rest.

These and other features of the invention will be best understood and appreciated from the following description of certain embodiments thereof selected for purposes of illustration and shown 45 in the accompanying drawings in which:

Fig. 1 is an enlarged end elevation, partially broken away, of a cofferdam constructed in accordance with my invention.

Fig. 2 is a perspective view of one of the barrier frames employed;

Fig. 3 is a transverse sectional view through a frame and illustrating the blanketing of the frame;

Fig. 4 is a perspective view of the cofferdam,

Fig. 5 illustrates the application of my invention to sloping and horizontal surfaces.

Fig. 6 illustrates the application of the invention to a horizontal surface, and

Fig. 7 is a fragmentary plan view illustrating a further feature of the invention.

In Figs. 1-4 I have illustrated the application of my invention to the formation of a water excluding cofferdam on and extending along a downwardly sloping bank 10 illustrated as having a concrete bottom 12. The apparatus employed comprises two end frames 14 and an articulated wall of frames 16 therebetween.

Each frame 16 is of triangular configuration (Fig. 3) and comprises bottom pieces 18, uprights 20 and relatively long and downwardly sloping pieces 22 covered to provide a continuous platform 24. The bottom corners of the frame are weighted by concrete blocks 26 and 28 and a plurality of buoyancy tanks 30 are carried in the upper portion of the frame. The frames are adapted to be connected together by cables 32 extending through pipe sleeves 34 mounted in alignment in the frames.

A sufficient number of frames 16 to form the required barrier are floated into alignment at the desired location and are held in such alignment by the cables 32 extending through the sleeves 34. The cables 32 join the frames into an articulated unit that can be easily floated to new locations. When the cables are loose the frames are permitted a considerable relative movement but the frames are held to a unit when the cables are tightened. The frames 16 are floated into place by means of the buoyancy chambers 30 and are sunk in the predetermined aligned position by displacing air with water in the chambers. End frames 14 are provided to cooperate with frames 16 and are sunk at the ends thereof to form the U-shaped barrier illustrated in Fig. 4.

The concrete bottom 12 is somewhat porous and water excluding blankets are employed for eliminating the inward seepage of water through the concrete. Blankets 36 are laid on and extend downwardly of the sloping bottom adjacent to and outwardly of the end frames 14. The outer end faces of these frames are sheathed over to provide a continuous supporting surface 37 and the outer end faces of the two outermost frames 16 at the ends of the barrier are likewise sheathed. These surfaces are covered with a water excluding blanket 38 extending downwardly thereover and outwardly therefrom in direct overlapping contact with the blankets 36.

Disposed on and along the platform 24 of the aligned frames 16 are a plurality of waterproof canvas blankets 40 in such overlapping relation as to form in effect a continuous blanket over the entire length of such surface. The top ends of these blankets are secured in place at 42 (Fig. 3) and the blankets, in rolled form, are adapted to be rolled downwardly thereof to cover the entire platform and a substantial area 44 of the bottom 10 therebeyond as illustrated in Fig. 1. The blankets are rolled on relatively heavy cores 43. These blankets also overlap the end blankets 38 and together therewith provide a U-shaped water barrier enclosing the area to be treated. Cables 46 cooperating with the blanket rolls 40 and wound on drums 48 carried by the frames

are employed for rolling the blankets down the platform 24.

The blocks 26 and 28 of cement, together with the buoyancy chambers 30 thereabove, not only aid in maintaining the frames 16 in upright position during the floating of the frames into place but also serve to hold the frames against backward tipping by the action and pressure of the water on the blankets.

It will be apparent that the water pressure on the top face of the blankets presses the blankets firmly into contact with the bottom 10 and forms a water excluding barrier. Under these conditions the only water that can reach the area enclosed by the barrier is such as may pass by slow seepage through the blankets and through the concrete 12. When the barrier and blankets are in final position, the water is pumped from the enclosed area. Such water as may seep into the area through the concrete beneath the relatively long distances covered by the blankets is extremely minor and is easily removed.

In Fig. 5 I have illustrated the employment of my invention on combined sloping and horizontal surfaces 50 and 52. A plurality of frames 54 are supported on cables 56 in aligned and articulated arrangement, like the frames 16, between suitable end frames like the frames 14 of Fig. 1. Vertical surfaces 58 on the forward sides of the frames are adapted to receive blankets 60 rolled downwardly thereover and outwardly along the bottom at 62.

In Fig. 6 I have illustrated the application of my invention to the exposing of an intermediate bottom surface 66. A plurality of frames 68 are supported on cables 70 in an aligned and articulated arrangement between suitable end frames. Oppositely disposed vertical surfaces 72 are provided at two sides of each frame and are adapted to receive blankets 74 rolled downwardly thereover and outwardly along the bottom at 76.

When employing the invention on mud or relatively soft bottoms, it is desirable to use additional supporting means for the blankets resting on the bottom. In Fig. 7 I have illustrated the employment of relatively adjacent rails 78 on the bottom beneath the blankets 60' thereby supporting the blankets against sagging movement through the bottom and beneath the blanket supporting surface 58' of the frame the area being exposed.

Having thus disclosed my invention what I claim as new and desire to secure by Letters Patent of the United States is:

1. A method of forming a cofferdam about a submerged surface area to be exposed in a body of water, which consists in providing about said area relatively adjacent and juxtaposed cooperating blanket supporting surfaces within the water and extending upwardly from the bottom of said body to above the water level, and excluding water from the area by attaching the outer free margin of rolled blanket material to the top portion of the combined surfaces above the water level and unrolling the material therefrom downwardly over the surfaces to the bottom of said area and from thence outwardly therefrom over the bottom.

2. A method of forming a cofferdam which includes the steps of floating an articulated row of frames, each having a laterally facing surface, into combined relation in which the combined laterally facing surfaces of the frames form a continuous supporting surface extending upward-

ly and longitudinally along the combined frames, sinking the frames to the bottom in such relation, and blanketing said supporting surface and the bottom adjacent thereto with a water-excluding fabric extending from the bottom to above the water level.

3. The method defined in claim 2 plus the sinking of end frames at and cooperating with the ends of said combined frames in a U-shaped arrangement enclosing a predetermined area, and blanketing the outwardly facing surfaces of the end frames with a water-excluding fabric cooperating with the first named fabric to exclude water from said area.

4. The method defined in claim 2 in which said supporting surface is blanketed by rolling a plurality of water-excluding blankets from above the water level downwardly and outwardly in

overlapping relation at their junction edges on and covering said supporting surface and said bottom adjacent thereto.
